UNITED STATES PATENT OFFICE

147,097

DESIGN FOR A HAIR BRUSH OR SIMILAR ARTICLE

Isadore O. Witte, Los Angeles, Calif., assignor to Le Vant Brush Company, Los Angeles, Calif., a corporation of California

Application December 16, 1946, Serial No. 135,544

Term of patent 3½ years

(Cl. D86—10)

To all whom it may concern:

Be it known that I, Isadore O. Witte, a citizen of the United States, residing in Los Angeles, in the county of Los Angeles and State of California, have invented a new, original, and ornamental design for a Hair Brush or Similar Article, of which the following is a specification, reference being had to the accompanying drawing, forming part thereof.

Fig. 1 is an elevational view of the back of a hair brush or similar article, showing my new design.

Fig. 2 is a side edge view thereof.

The dominant features of the design are embodied in the parts shown in full lines.

I claim:

The ornamental design for a hair brush or similar article, substantially as shown and described.

ISADORE O. WITTE.
